INTERMITTENT FILM FEED

Charles W. Dyer, Stratton, Maine

Application July 26, 1946, Serial No. 686,521

6 Claims. (Cl. 74—84)

1

My present invention relates to an improved intermittent film feed of the type adapted to feed perforated film strips such as that employed in motion pictures and which is especially designed to feed such film without damage to the film and the sections between the perforations.

In the accompanying drawings I have illustrated one complete example of the physical embodiment of my invention according to the best mode I have thus far devised but it will be understood that various changes and alterations may be made in the exemplified structure within the scope of the appended claims.

In the drawings:

Figure 1 is a top plan view of the structure of my invention showing the intermittent feed assembly approaching feeding position.

Figure 2 is a side elevational view thereof.

Figure 3 is a top plan view of the feed assembly in feeding position.

Figure 4 is a side elevational view thereof; and

Figure 5 is a detail sectional view at line 5—5 of Figure 3.

Referring now to the drawings in detail wherein like characters indicate like parts I have illustrated the intermittent feed of my invention as embodying a shaft 2 which is rotated from the power gear 4 to rotate the driving disk 6.

This disk is formed with a shallow peripheral depression 8 having bottom surfaces 10 and 11 that are preferably convexed and converge downwardly to their meeting point at the center line 9 of the depression. These surfaces merge, at the opposite ends of the depression, into the flat upper surface of disk 6. Adjoining the inner edge of this depression 8 I employ a low abutment or cam 12 arcuate in plan and having walls converging upwardly to the apex 14, said walls being preferably concaved.

The intermittently driven member comprises the polygonal element 16 secured to the shaft 18 and having peripheral faces 20. Element 16 is here shown as octagonal, but is not necessarily so. The faces 20 which are tangential to the center of the driven member meet at points 22 and a circular series of pins 24 is radially disposed about the center of the member, each pin being located along the line from the center of the member 16 to the center of the face.

A single step movement of the parts will be considered. For the greatest part of a single rotation of disk 6, one of the faces 20 of element 16 will be in sliding contact with the smooth top surface of the disk. Therefore, element 16 will not be given any movement during this part of a rotation of disk 6. Further, not only will element

2

16 be stationary at this time, but it will in fact be held against any movement, because of the sliding fit of said face 20 against the disk surface. In this way, movement of the element 16 by momentum is eliminated.

Continuing, cam 12 now engages a pin 24 (Figs. 1 and 2) and therefore begins to move element 16. When this occurs, a corner or point 22 begins to move into depression 8 and the parts move into the position of Figs. 3 and 4.

As the cam continues to move element 16, the cam clears the pin which it has engaged. At the same time, the trailing surface of depression 8 (here shown as surface 10) engages the corner 22, which is still in the depression 8. Thus, cam 12 is no longer moving element 16, the surface 10 now taking over the task of moving element 16 through the rest of its step movement.

The surface 10 remains in engagement with corner 22, and therefore moves the element 16 through the rest of its step movement, until corner 22 is elevated into a plane common with the plane of the disk surface, at which time the face 20 next following the corner will also move into said plane. The step movement is now completed, and there is again a sliding fit of element 16 against disk 6. Succeeding operations as described above result in the intermittent feed of the film.

30 The film is not shown, nor have I illustrated the conventional sprocket wheel that engages the film. This wheel, however, would be carried by the shaft 18 for rotation therewith.

The preferred concavity of the faces of cam 12, and convexity of the surfaces 10 and 11, is for the purpose of starting the feed motion slowly, speeding it up at the middle, and slowing it down toward the end of the feed.

Some advantages of the mechanism, and its action, are the fact that it is simple and is not hard on the feed holes of the films (as is the case, for example, in claw-type feeds, which are most generally used). Additionally, the mechanism provides for a full control of the driven element 16 at all times, momentum never being permitted to assert itself, since the disk 6 both produces controlled motion of the element 16 and serves as a brake against further movement. The speed, additionally is controllably varied through 50 a single step movement of element 16.

Having thus fully described my invention what I claim as new and desire to secure by Letters Patent is:

1. An intermittent film feed comprising a 55 driven disk formed with a peripheral depression, an abutment on the disk adjacent the depression,

a driven element polygonally shaped to define corner portions, and angularly related to the disk, and a circular series of pins on the element in the path of movement of the abutment, said abutment adapted to engage a pin, and the depression surface adapted to engage a corner portion of the element in succession, to impart movement to said driven element.

2. An intermittent film feed comprising a driven disk formed with an arcuate depression having downwardly converging walls, an abutment on the disk adjacent the depression formed with upwardly converging walls, a driven element polygonally shaped to define corner portions, and a circular series of pins disposed radially of the center of the element and in the path of movement of the abutment, said abutment adapted to engage a pin and a wall of the depression adapted to engage a corner portion of the element in succession, to impart movement to said driven element.

3. An intermittent film feed comprising a driven disk formed with a peripheral depression, an abutment on the disk adjacent the depression, said abutment having concaved walls, a driven element polygonally shaped to define corner portions and angularly related to the disk, a circular series of pins on the element in the path of movement of the abutment, said abutment adapted to engage a pin, and the depression surface adapted to engage a corner portion of the element in succession, to impart movement to said driven element.

4. An intermittent film feed comprising a driven disk formed with a peripheral depression having convexed and downwardly converging bottom surfaces, an abutment on the disk adjacent the depression formed with concaved and upwardly converging walls, a driven element polygonally shaped to define corner portions, and a circular series of pins disposed radially of the center of the element and in the path of movement of the abutment, said abutment adapted to

engage a pin and the depression surface adapted to engage a corner portion of the driven element in succession, to impart movement to said driven element.

5. An intermittent film feed comprising a driven disk formed with a peripheral depression, an abutment on the disk adjacent the depression, a driven element polygonally shaped to define corner portions and angularly related to the disk, and means carried by the element in the path of movement of the abutment, said abutment adapted to engage said means, and the depression surface adapted to engage a corner portion of the element in succession to impart movement to said element.

10 6. An intermittent film feed comprising a driven disk formed with a peripheral depression, an abutment on the disk adjacent the depression, a driven element polygonally shaped to define corner portions and angularly related to the disk, and means carried by the element in the path of movement of the abutment, said abutment adapted to engage said means, and the depression surface adapted to engage a corner portion of the element in succession to impart movement to said element, said disk having a smooth surface but for the depression and abutment, said surface adapted to engage a peripheral face of the driven element in sliding contact when the abutment and depression are disengaged from the driven element.
